UNITED STATES PATENT OFFICE.

WILLIAM L. GILE, OF LUDINGTON, MICHIGAN.

HYDRAULIC CONTROLLING MEANS FOR PROPELLERS.

1,078,092.

Specification of Letters Patent.

Patented Nov. 11, 1913.

Application filed August 17, 1910. Serial No. 577,686.

To all whom it may concern:

Be it known that I, WILLIAM L. GILE, a citizen of the United States, residing at Ludington, county of Mason, State of Michigan, have invented a certain new and useful Improvement in Hydraulic Controlling Means for Propellers, and declare the following to be a full, clear, and exact description of the same, such as will enable others skilled in the art to which it pertains to make and use the same, reference being had to the accompanying drawings, which form a part of this specification.

The propellers of motor boats are sometimes built so that the blades may be adjusted about axes at right angles to the axis of rotation so as to make it possible to drive the boats forward or backward or to hold them stationary while the engines are running, without making it necessary to use reversing gear or clutch mechanism except such as may be required to control the propeller blades.

My invention, specifically considered, has for its object to provide a simple and reliable actuating and controlling system for propeller blades of this type.

The various features of novelty whereby my invention is characterized will herein after be pointed out with particularity in the claims; but for a full understanding of my invention and of its object and advantages, reference may be had to the following detailed description taken in connection with the accompanying drawings, wherein:

Figure 1 is a view partly in plan and partly in section showing a preferred embodiment of my invention; Fig. 2 is a section taken on line 2—2 of Fig. 1; Fig. 3 is a section through the stationary base member; Fig. 4 is a vertical section through the controlling valve; and Fig. 5 is a plan view of the movable member of the valve.

Referring to the drawings, A and A' represent two propeller blades revolvably mounted in a hub B carried upon the end of a propeller shaft C. The propeller blades are mounted in such a manner that they may be rotated about axes at right angles to the axis of the propeller shaft, thus permitting them to be adjusted to drive in either direction or to feather and thus produce no driving movement. If desired, the blades can of course be adjusted to any position intermediate between the full forward and the full reverse positions.

D is a sleeve surrounding the propeller shaft and arranged to be moved axially thereof. The sleeve is provided with oppositely extending forks d and d' which are adapted to receive pins a and a' carried eccentrically upon the inner ends of the propeller blades. As the sleeve is moved back and forth along the shaft, the forks or jaws move the pins on the propeller blades and turn the blades. All of these parts are now old and well known and, since the present invention is not concerned with the details of the propeller blade mounting, it is believed that this brief description will suffice. The sleeve extends through the stern bearing E along the bottom of the boat, and at a suitable point along its length, it passes freely through a transverse yoke F.

D' and D² are collars clamped upon the sleeve on opposite sides of the yoke so as to hold the sleeve and yoke against relative movements lengthwise of the sleeve. This yoke forms the means of connection between the sleeve and a hydraulic controlling and actuating system. For the sake of brevity I have illustrated only a single type of system, one to which the yoke is applicable. It will of course be understood, however, that instead of the yoke I may employ any other suitable means for connecting a hydraulic controlling and actuating system to the sleeve.

The embodiment of my invention illustrated is one in which the thrust and pull upon the adjusting sleeve is balanced and to this end I connect the ends of the yoke with double-ended pistons or plungers lying on opposite sides of the sleeve. The pistons or plungers G and G' serve to move the sleeve in one direction while the pistons G² and G³ are adapted to produce a movement in the opposite direction. Each of the pistons or plungers is movably mounted in a suitable cylinder, these being indicated at H, H', H² and H³ respectively. The cylinders may conveniently be made up of tubular body members h having caps h' and h² screwed or otherwise secured upon the ends thereof. The caps h² are provided with openings h³ large enough to permit the plungers to pass therethrough. The caps h' are provided with inlet ports to be hereinafter described. Each of the cylinders is provided with an outlet port which is adapted to be controlled by the corresponding plunger or piston and is so located that

it will be uncovered by the corresponding plunger or piston when the latter has reached the end of its working stroke. These outlet ports are indicated at I, I', I² and I³ respectively.

K is a base plate which is provided with four posts or pedestals, L, L', L², and L³ each of which has a clamping jaw at its upper end adapted to receive one of the cylinders, the jaws being indicated at l, l', l² and l³. Each of the pedestals is cored out so as to provide a passage-way which communicates with the outlet port of the corresponding cylinder when the cylinder is clamped in place. These passages are indicated at M, M', M² and M³. The base plate itself is also cored out so as to provide a longitudinal conduit M⁴ which is connected to the passages M to M³ by means of branch conduits m to m³ which are also formed by coring out the base plate.

N is a pump for pumping oil or other suitable liquid, the suction end of the pump being indicated at n and the discharge end at n'.

O is a valve having four ports O' to O⁴. The suction end of the pump is connected to the port O³ by a pipe P. A branch pipe p leading from the pipe P communicates with the passage M⁴ in the base plate. The discharge end of the pump is connected to the port O' by means of a pipe P', the ports O³ and O' being diametrically opposed to each other. The port O² is connected to a pipe which opens into the head h' of the cylinder H² and constitutes the inlet port for said cylinder. p² is a branch pipe leading from the pipe P² and opening into the head h' of the cylinder H³, and thus constituting the inlet port for the latter cylinder. The port O⁴ is connected with a pipe P³ which extends to and opens into the head h' of the cylinder H and thus forms the inlet port for that cylinder. A branch pipe p³ leads from the pipe P³ into the head h' of the cylinder H' and forms the inlet port for this cylinder. The ports O² and O⁴ in the valve are arranged diametrically opposite each other and are spaced 90 degrees apart from the ports O' and O³.

Q is the movable member of the valve and it is constructed and arranged so as to permit it to place either port in communication with the next adjacent port, at the same time connecting together the two remaining ports.

The entire system is adapted to be filled with oil or other suitable liquid.

Assuming that the pump is operating so as to tend to produce a circulation through the system and that the valve member Q is in the position indicated in Fig. 1: it will be seen that liquid is being forced through the pipe P' through the valve through the pipe P² and into the cylinders H² and H³.

The pistons are illustrated in the extreme positions to which they are moved by pressure in the cylinders H² and H³ so that the ports I² and I³ are opened. The oil flowing into these cylinders therefore passes through the ports I² and I³ and returns to the suction end of the pump through the passages in the base member, pipe p, pipe P. It will be seen that the cylinders H and H' are also connected to the suction side of the pump through pipe P³ and the valve so that there can be no pressure in these cylinders. If now the valve is turned 90 degrees into the dotted line position indicated in Fig. 1, the discharge end of the pump is connected with the cylinders H and H' through connections which are readily traced, while the inlet ports of the other two cylinders are connected to the suction side of the pump. The liquid will now be forced into the cylinders H and H' and will be withdrawn from the cylinders H² and H³ so that the pistons are forced toward the right, carrying the sleeve with them and shifting the positions of the propeller blades. When the pistons have completed their stroke toward the right the ports I and I' are uncovered so that a steady circulation of the liquid is maintained. This circulation of the liquid is very important for the reason that any retrograde movement of the pistons is avoided because as soon as they start back and cover up the outlet ports, the pressure in the system becomes effective to return them to the ends of their working strokes. The thickness of the member Q of the valve, measured circumferentially, is less than the width of the ports in the valve casing so that the valve can never assume a position in which the circulation in the system is interrupted. This construction also has the advantage that it permits the pressure on the opposing pistons to be equalized at any time so as to maintain the pistons in any position into which they have been moved. Thus, when it is desired to stop the boat without shutting down the engine, the pistons are carried into the mid-position and then the valve is turned so as to register with the ports O' and O³. If the adjustment of the propeller blades has not been quite right the valve can be turned a little to the right or to the left, as conditions may require, thus producing a differential pressure of any desired degree upon the pistons and carrying the blades slowly back to the point where no movement of the boat results.

In Figs. 4 and 5 I have illustrated the valve more in detail. I prefer to provide the member Q with two disks Q' and Q² which lie above and below the vane or cross member, thus giving a large bearing surface in the casing and reducing the danger of leakage to the minimum.

While I have illustrated and described

with particularity only a single form of my invention I do not desire to be limited to the specific details so illustrated and described; but intend covering all constructions and arrangements which fall within the terms employed in the definitions of my invention constituting the appended claims.

What I claim is:

1. In combination, a member to be moved, two pistons connected to said member, cylinders in which said pistons are mounted, each of said cylinders having an inlet port and an outlet port, a pump, a controlling valve, and pipes connecting the said ports and the valve to the pump, said pipes being adapted to be filled with a liquid, and said controlling valve having a position wherein it connects one of said inlet ports to the discharge side of the pump and simultaneously connects the corresponding outlet port and the other inlet port to the suction side of the pump.
2. In combination, a member to be moved, two pistons connected to said member, cylinders in which said pistons are mounted, each of said cylinders having an inlet port and an outlet port, a pump, a controlling valve and pipes connecting said ports and the valve to the pump, said pipes being adapted to be filled with a liquid, and said controlling valve having positions wherein it connects either of said inlet ports to the discharge side of the pump and simultaneously connects the corresponding outlet port and the other inlet port to the suction side of the pump.
3. In combination, a member to be moved, two pistons connected to said member, cylinders in which said pistons are mounted, each of said cylinders having an inlet port and an outlet port, a pump, a controlling valve, and pipes connecting said ports and the valve to the pump, said pipes being adapted to be filled with a liquid, said controlling valve having positions wherein it connects either of said inlet ports to the discharge side of the pump and simultaneously connects the corresponding outlet port and the

other inlet port to the suction side of the pump, said valve also having a position wherein it connects all of said ports both to the suction side of the pump and to the discharge side of the pump.

4. In combination, a member to be moved, two pistons connected to said member, cylinders in which said pistons are mounted, each of said cylinders having an inlet port and an outlet port, a pump, a controlling valve, pipes extending from the suction side and the discharge side of the pump to said valve and to said ports, said pipes being adapted to be filled with a liquid, said controlling valve having a position wherein it connects one of said inlet ports to the discharge side of the pump and simultaneously connects the corresponding outlet port and the other inlet port to the suction side of the pump, and said valve also having a position wherein it connects all of said inlet ports both to the suction side of the pump and to the discharge side of the pump.

5. In combination, an element to be moved, a piston member connected to the aforesaid element and having two opposed piston faces, a cylinder apparatus in which said piston is movably mounted, said cylinder apparatus having an inlet port and an outlet port on the same side of each of said piston faces, a pump, a controlling valve, and pipes connecting the said ports and the valve to the pump, said pipes being adapted to be filled with a liquid, and said controlling valve having a position wherein it connects one of said inlet ports to the discharge side of the pump and simultaneously connects the corresponding outlet port and the other inlet port to the suction side of the pump.

In testimony whereof, I sign this specification in the presence of two witnesses.

WILLIAM L. GILE.
